UNITED STATES PATENT OFFICE

95,955

DESIGN FOR A DISPLAY RACK

Norman E. Heil, Paterson, N. J.

Application May 16, 1934, Serial No. 51,811

Term of patent 7 years

To all whom it may concern:

Be it known that I, Norman E. Heil, a citizen of the United States, residing at Paterson, in the county of Passaic and State of New Jersey, have invented a new, original, and ornamental Design for Display Racks, of which the following is a specification, reference being had to the accompanying drawing, forming part thereof.

In the drawing:

Figure 1 is a front elevation of the display rack

showing my new design having flat shelves which extend back the whole depth of the rack.

Figure 2 is a top plan view of the same.

Figure 3 is a side elevation thereof.

I claim:

The ornamental design for a display rack as shown and described.

Signed at Paterson, New Jersey, this 2 day of April, 1934.

NORMAN E. HEIL.
